CLAIM

We claim the ornamental design for a vacuum cleaner wand, as shown and described.

DESCRIPTION

FIG. 1 is a top perspective view of a vacuum cleaner wand showing our new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,
FIG. 7 is a front view thereof.

The broken lines shown in the drawings illustrate portions of a vacuum cleaner or portion thereof that form no part of the claimed design.

1 Claim, 4 Drawing Sheets
